UNITED STATES PATENT OFFICE

137,973

DESIGN FOR A PLOTTING BOARD

Ingram Victor Stovern, Sheboygan, Wis., assignor to Estate of Harold L. De Lisle, a trust, doing business as Engineering Sales Company, Sheboygan, Wis.

Application March 3, 1944, Serial No. 112,778

Term of patent 14 years

(Cl. D52—1)

To all whom it may concern:

Be it known that I, Ingram Victor Stovern, a citizen of the United States, residing at Sheboygan, in the county of Sheboygan and State of Wisconsin, have invented a new, original, and ornamental Design for a Plotting Board, of which the following is a specification, reference being had to the accompanying drawing, forming part thereof.

Fig. 1 is a plan view of a plotting board showing my new design; and

Fig. 2 is a front elevational view thereof.

I claim:

The ornamental design for a plotting board, as shown.

INGRAM VICTOR STOVERN.
